UNITED STATES PATENT OFFICE

ARMISTEAD R. LONG, OF SCARBRO, WEST VIRGINIA

TEMPORARY EXTENSION FOR MINE RAILWAYS

Application filed April 27, 1929, Serial No. 358,641. Renewed October 20, 1930.

This invention relates to improvements in temporary extensions for mine trackways.

The primary object of this invention is the provision of a practical type of temporary trackway extension, preferably used in mines where the trackway must be advanced slowly, as the wall of coal is removed, including conventional lengths of rails of stock cross section which are inverted and connected for slidable adjustment to the adjacent permanent rails of the trackway; special ties being used to brace the inverted temporary track sections in a gauged and efficient relation, with improved special tie means to anchor the temporary rails for slid- able adjustment with respect to the ends of permanent rails.

Other objects and advantages of this invention will be apparent during the course 20 of the following detailed description.

In the accompanying drawings, forming a part of this specification, and wherein similar reference characters designate corresponding parts throughout the several views.

25 Figure 1 is a perspective view of the improved temporary track extension unit showing its relation to the end rails of a permanent track system.

Figure 2 is a view of the temporary track extension unit in a further adjusted position than that shown in Figure 1, and also showing an improved type of car stop thereon.

30 Figure 3 is a perspective view of a special tie used for detachable connection to inverted tracks, to hold a pair of the same in properly gauged relation forwardly of the rails of the permanent track section.

Figure 4 is a perspective view of a special 35 type of tie, showing clips used to hold the inverted temporary track extension rails to the permanently attached rails of a roadbed.

Figure 5 is an enlarged fragmentary view, partly in section, showing the manner in which the anchor clips of the special tie of Figure 3 grip an inverted temporary extension rail of the extension trackway system.

Figure 6 is a fragmentary view, partly in section, showing the relation in which the special tie of Figure 4 anchors the inverted

temporary rails against the permanently attached rails of the permanent trackway.

Figure 7 is a fragmentary view, partly in section, of the anchor clip and clamps at an end of special tie shown in Figure 4, the view 55 being taken substantially on the line 7—7 of Figure 5.

In the drawings, wherein for the purpose of illustration is shown only a preferred embodiment of the invention, the letter A may 60 generally designate a permanent trackway, preferably of the mine type, whereon mine cars, or cutting or loading machinery may pass, in approach to the coal wall which is being mined. In connection therewith the 65 improved trackway extension unit B, of a temporary character, is used, in adjustably connected relation upon the rails of the permanent trackway A; being adjusted in the direction of the coal wall, as the coal is 70 mined therefrom, for the purpose of facilitating approach of the cars and machinery thereto.

With reference to the permanent trackway A, the same preferably comprises end rails 75 10 and 11, which are permanently attached on tie 11^a, of conventional character, which have usual clips 12 thereon, preferably at the inner and outer sides thereof, anchored to the base flanges at the inner and outer sides 80 of the web of the permanent rails 10 and 11, as can readily be understood. These ties 11^a

may be of the metal type, such as are usually employed in mines, and the use of the word "permanent" is restricted to the use that is 85 applicable in connection with the laying of tracks in mines, where it is desired to provide a permanent trackway system, which is not permanent in the sense that the trackway and its details thereof cannot be removed, but 90 is permanent in the sense that the rails and ties are used in their usual relation for transporting cars and other machinery thereover, and intended to remain in place until the supply of coal is depleted, or the trackway 95

is no longer of use. In this connection the extension unit B is used to designate an extension of the so-called permanent trackway system, which is temporary in character, inasmuch as it is used to adjust the trackway 100

over the short distance between the ends of the permanent rails 10 and 11 and the wall of coal which is being mined or worked upon. Inasmuch as this distance is generally less than the length of conventional rail sections, the improved temporary trackway B has been found to efficiently fulfill all requirements under practical conditions of use.

In the temporary trackway unit B, rail lengths 15 and 16 are provided, which have exactly the same cross section as the rail sections 10 and 11 above described as constituting part of the permanent trackway system, except that they are inverted. In other words, each of the rails 10, 11, 15 and 16 is provided with a foot portion 20, a web 21, and a head or ball 22, arranged according to the usual cross section of a car supporting rail. The foot 20 of course has the relatively thin base flanges at each side of the plane of the web 20, and the head 22 may vary in cross section as desired; it being usual to provide the same of narrower width than the width between the longitudinal edges of the foot 20.

The extension rails 15 and 16, as above mentioned, are inverted, and since they are of the same cross section as the permanent rails, and are intended to overlap the ends of the permanent rails, it follows that the heads of the overlapping rails bear against the foot and web of the adjacent rails, as shown in Figure 6 of the drawings. The extension rails 15 and 16 lie at the outer sides of the permanent end rails 10 and 11, and it is to be noted that the feet portions or bases 20 of the inverted temporary rails 15 and 16 lie close to the top surfaces of the heads of the permanent rails 10 and 11, although in a plane thereabove.

The extension unit B preferably includes the special tie and anchor clip constructions C for holding and engaging the rail extensions 15 and 16 to each other, forwardly beyond the ends of the permanent end rails 10 and 11. Each tie and anchor clip construction C preferably includes a metal tie body 10^a, although it may be of other material if desired. However, inasmuch as the device is principally used in mining, where all ties and rails are placed more or less temporary, it is preferred that the metal type of channel tie body be used, such as shown at 10^a. It is not of unusual construction, except with reference to the special anchor clips and clamps used thereon. At each end of the tie body 10^a there is placed a permanently anchored or riveted holding or anchor clip 30, and a pivoted locking lever or clamp 31. They are shaped and formed so as to engage the ball or head of the inverted temporary rail and the web of the inverted rail, along the web preferably extending the height thereof, almost to immediately adjacent the base of the inverted temporary rail, and ref-

erence may be made to Figure 5 in this connection.

The anchor clips 30 and 31 are so placed upon the tie body 10^a that the permanently attached clips 30 engage one of the temporary rails at the outer side and the other temporary rail at the inner side, and similarly the pivoted anchor lever type of clips 31 engage the extension rails, one of them at the inner side and the other at the outer side. As shown for the ties C of Figures 2 and 3, the permanently attached clips 30 are placed to engage the temporary rail extensions 15 and 16 at the inner and outer sides respectively, and the lever type of clips 31 engage the rail extensions 15 and 16 at the outer and inner sides respectively.

The anchor clips 30 are of the type shown in Figures 5 and 7, each including a base portion 35 of about the same width as the tie body 10^a, and anchored thereto as by a pair of rivets 36 and 37^a. The said anchor clips 30 furthermore include the angle flange portions 37 adapted to engage the normal outer and under sides of the normal head portion 22 of the inverted extension rail, and furthermore include the upwardly extending web engaging flange or portion 39 adapted to extend throughout the major height of the rail web 21, for bracing and reinforcing the inverted rail in position. Thus, the permanently attached anchor clips each include a body attached to the tie, and portion 37 and 39 adapted to snugly receive therein the inverted ball or head of the rail and the web thereof.

Referring to the pivoted locking lever type of clip 31, the same includes an elongated body 40, which is preferably narrower than the width of the tie body 10^a, and anchored to one side of the medial axis of the tie body 10^a, by means of a rivet or other type of pivot connection 42. This pivot connection 42 is pivoted eccentrically upon the body 40 of the locking clip 31, to one side of the medial center line thereof, in order to provide for a more efficient rail attachment and detachment. This is best shown in Figure 7. As shown in Figure 5 and elsewhere, the outer end of the body 40 is upturned at 45 in acute angular relation, to facilitate engagement of a tool therewith for placing the pivoted anchor clip in or out of rail engagement. At its rail engaging end the anchor clip 31 is provided with an upstanding normal web engaging shank or portion 47, which at the juncture with the body 40, is provided with an angled rail head or ball engaging portion 48, adapted to engage the sides and normal under-surface of the head 22 of the rail, as shown in Figure 5 of the drawings. The web engaging shank 47 is of slightly less height than the height of the web 21, to engage the said web effectively throughout its height, and opposed to the web engaging portion 39 of the other anchor clip 30. The web engag-

ing flange or shank 47 is convexly arcuated at 50, at opposite corners thereof facing the web, to facilitate riding of engagement of the pivoted anchor clip 31 against the web of the rail, 5 and to provide an efficient connection, as can readily be understood. By making both of the corners 50 arcuate in this manner, it will be unnecessary to punch the body portion 40 at any particular side of its longitudinal axis, 10 for receiving the pivot rivet or pin 42.

From Figure 7 it will be noted that the pivoted anchor clip is placed upon the body 10^a of the tie in such relation that one longitudinal edge thereof aligns with a side edge 15 of the metal tie.

The arrangement of the anchor clips on the special tie C is shown in Figure 6, and for the rail extension 16 the permanently attached clip 30 engages at the outer side of said 20 rail and the pivoted anchor clip 31 engages at the inner side of said rail. Conversely, for the extension rail 15 the permanent anchor clip 30 engages at the inner side of said rail and the pivoted anchor clip or lever 31 engages 25 at the outer side of said rail; the said clips engaging the inverted extension rails in the relation above described, and as is shown in Figure 5 of the drawings.

As the extension rails 15 and 16 are slid 30 along the permanent end rails 10 and 11 of the trackway A, to extend the rail system to the very wall from which coal is being mined, the special ties C are added, preferably on four-foot centers, as can be seen from Figures 35 1 and 2 of the drawings.

The special tie D shown in Figure 4 of the drawings is preferably applied to the rear ends of the extension rails 15 and 16, where they overlap with the end rails 10 and 11 of the permanent trackway system. This is 40 shown in Figure 6 of the drawings, and the application is shown in the perspective views of Figures 1 and 2 of the drawings, wherein it is shown that this special tie D is applied to the overlapping permanent and extension rails just rearwardly of a permanent tie 11^a at the extreme ends of the end rails 10 and 11. As shown in Figure 6, the extension rails 15 and 16 are applied in inverted relation 45 along the outer sides of the permanently placed rails 10 and 11, and at one end the tie body 10^b of the tie construction D is applied with a permanently attached rail anchor clip 60, of the same nature and construction as the anchor clips 30 above described, having a plurality of rivets 61 which secure the same on the body 10^b at one end of the tie, and having a relatively high web 50 engaging shank 62 which engages through- 60 out the height of the web 21 of the inverted rail 16, and at a juncture of the portion 62 with the body of the clip 60 there is provided an angled head engaging portion 64, which engages the ball of the rail. No clips 65 are provided for engaging the inner sides

of either of the rails, but at its opposite end the tie body 10^b is provided with a pivoted anchor clip or lever 66, which is eccentrically pivoted at 67 to the tie body 10^b in the same relation as above described for the clip 31. 70 It possesses the same characteristics, having a tool engaging end 68, and a web engaging shank 69 adapted to engage the web of the inverted rail substantially throughout the height thereof. It furthermore has the angled portion 70^a adapted to engage the ball portion of the inverted rail; the same being convexly arcuate at 72^a to facilitate its placement, for locking the rails together. It is readily observable that the improved special tie D serves a very important function 80 of preventing the rear ends of the extension rails from spreading with respect to the permanent end rails 10 and 11.

From the foregoing description of this invention it is apparent that an improved type of extension unit for track constructions has been provided, which will eliminate the usual expedients provided for track extensions, such as short rails and temporary wood rails, 90 commonly called "jumpers." Of course, while realizing that there have been suggested heretofore a number of rail extensions, such as by re-arranging, and even inverting usual rail lengths, in the main they have been found unsatisfactory due to the manner in which they have been attached, and the special means for accomplishing such attachment. With the use of the special ties of my invention, I have provided an improved 100 track extension, of a temporary nature, which is extremely practical and recognizes all practical considerations in connection with the laying and extension of mine tracks. The device is one which may be readily adjusted, easily applied, and quickly disconnected. It facilitates loading, saves time, and may be used to support cars to be loaded, loading mechanisms, and cutting mechanisms. 105

Various changes in the shape, size, and arrangement of parts may be made to the form of invention herein shown and described, without departing from the spirit of the invention or the scope of the claims. 110

I claim:

1. In a railway extension unit a tie having releasable clamps separated to receive therebetween the head and web portions of an inverted rail in an unobstructing relation with the normal foot portion of said rail, one of said clamps comprising a pivoted clamp swingable in the plane of the tie into and out of engagement with the head and web of an inverted rail placed on the tie. 120

2. In a trackway extension unit for temporary use the combination of a tie having relatively spaced rail engaging clamps at each end thereof, said rail engaging clamps at each end of the tie being formed to receive 125

therebetween the head and web portions of an inverted temporary rail.

3. In a trackway extension unit for temporary use the combination of a tie having relatively spaced pairs of rail engaging clamps at each end thereof, said rail engaging clamps at each end of the tie being formed to receive therebetween the head and web portions of an inverted temporary rail, one of said rail clamps at each end of the tie being pivoted to the tie for movement in the plane of the tie toward and from the other clamp adjacent thereto.

4. In a trackway extension unit for temporary use the combination of a tie having relatively spaced pairs of rail engaging clamps at each end thereof, said rail engaging clamps at each end of the tie being formed to receive therebetween the head and web portions of single inverted temporary rails, one of said rail clamps at each end of the tie being pivoted to the tie for movement in the plane of the tie toward and from the other clamp adjacent thereto, said other clamp at each end of the tie being permanently secured in inverted rail receiving relation upon said tie.

5. In a trackway extension unit for temporary use, a tie, a rail having a base, a web and a head narrower than the base, a clip fixedly secured immovably to the tie and turned up at an end to engage against the head and web only of said rail when inverted, and a pivoted clamping clip secured to said tie spaced from the first mentioned clip and in such relation as to clamp against the head and web at the opposite side of said rail when inverted for forcing the rail against the upturned end of the first mentioned clip in the relation described.

6. In a trackway extension unit for temporary use the combination of a tie, a pair of inverted rails of normal cross section adapted to be supported upon said tie in properly gauged relation, permanently affixed rail anchor clips upon said tie one being adapted to engage one of the inverted rails at the head and web portions thereof at the outer side and the other of said clips adapted to engage the head and web portions of the other inverted rail at the inner side thereof, and detachable clamping clips on said tie adapted to engage said inverted rails at the head and web portions thereof at the sides opposite the engagement of the permanent clips therewith.

7. In a trackway construction the combination of a tie adapted to receive rails thereon in properly gauged relation, said tie at opposite ends thereof having rigidly affixed anchor clips thereon for engaging the rails, one of the rails at the outer side and the other at the inner side, and movable wedge clamping clips on the tie in spaced relation with the first mentioned clips adapted to engage

said rails at the opposite sides from the clips first mentioned.

8. In a trackway construction the combination of a tie adapted to receive rails thereon in properly gauge relation, said tie at opposite ends thereof having rigidly affixed anchor clips thereon for engaging the rails, one of the rails at the outer side and the other at the inner side, movable wedge clamping clips on the tie in spaced relation with the first mentioned clips adapted to engage said rails at the opposite sides from the clips first mentioned, said last mentioned clips being pivoted and having upturned rail engaging ends movable towards and away from the adjacent clips as the last mentioned clips are swung upon their pivots.

9. In a temporary track extension unit the combination of a pair of inverted rails including downwardly facing head portions, web portions, and upwardly facing base portions, and a tie construction upon which the said rails rest at their head portions including spaced clips at each of the ends thereof for engaging the head and web portions of the inverted rails therebetween, said spaced clips at each of the ends of said tie including one rigidly attached immovable clip, and a pivoted wedge anchoring clip having a rail engaging portion which will urge the inverted rail head and web against the rigidly attached clip adjacent thereto.

10. In a temporary track extension unit the combination of a pair of inverted rails including downwardly facing head portions, web portions, and upwardly facing base portions, a tie construction upon which the said rails rest at their head portions including spaced clips at each of the ends thereof for engaging the head and web portions of the inverted rails therebetween, said spaced clips at each of the ends of said tie including one rigidly attached immovable clip, and a pivoted wedge anchoring clip having a rail engaging portion which will urge the inverted rail head and web against the rigidly attached clip adjacent thereto, each clip having an upstanding end thereon which may engage about the adjacent portion of the inverted rail head and along the web for the major height of the web.

11. A rail clamp provided with an elongated body having a pivot between the ends thereof, said body at one end being upturned and shaped to receive thereunder and thereagainst the head flange and web of an inverted rail with the base of the rail overhanging the same.

12. A rail clamp provided with an elongated body having a pivot between the ends thereof, said body at one end being upturned and shaped to receive thereunder and thereagainst the head flange and web of an inverted rail with the base of the rail overhanging the same, the pivot axis of the body

of said clamp being offset laterally of the longitudinal center line of the clamp body.

13. A rail clamp provided with an elongated body having a pivot between the ends thereof said body at one end being upturned and shaped to receive thereunder and thereagainst the head flange and web of an inverted rail with the base of the rail overhanging the same, the pivot axis of the body of said clamp being offset laterally of the longitudinal center line of the clamp body, and the upturned end at the corner thereof which is adapted to wedge against the rail being convexly arcuate.

14. A rail clamp provided with an elongated body having a pivot between the ends thereof, said body at one end being upturned and shaped to receive thereunder and thereagainst the head flange and web of an inverted rail with the base of the rail overhanging the same, the pivot axis of the body of said clamp being offset laterally of the longitudinal center line of the clamp body, the upturned end at the corner thereof which is adapted to wedge against the rail being convexly arcuated, the end of the body opposite the first mentioned upturned end being upturned for tool engaging purposes.

15. In a track construction, the combination of a tie, and a rail anchor clip pivoted between its ends on the tie and having an upturned rail engaging portion at one end formed to receive the flange at one side of the head of an inverted rail thereunder and thereagainst, said end extending upwardly a sufficient distance to receive thereagainst the web of the inverted rail throughout the major height of said web.

16. In a track construction, the combination of a tie, a rail anchor clip pivoted between its ends on the tie and having an upturned rail engaging portion at one end formed to receive the flange at one side of the head of an inverted rail thereunder and thereagainst, said end extending upwardly a sufficient distance to receive thereagainst the web of the inverted rail throughout the major height of said web, and a permanently secured clamp on the tie adapted to engage the opposite side of the inverted rail so that the first mentioned clamp may wedge the inverted rail into position thereagainst.

17. In a track construction, the combination of a tie, a rail anchor clip pivoted between its ends on the tie and having an upturned rail engaging portion at one end formed to receive the flange at one side of the head of an inverted rail thereunder and thereagainst, said end extending upwardly a sufficient distance to receive thereagainst the web of the inverted rail throughout the major height of said web, a permanently secured clamp on the tie adapted to engage the opposite side of the inverted rail so that the first mentioned clamp may wedge the in-

verted rail into position thereagainst, said second mentioned clamp having an upturned end shaped to receive thereagainst the flange portion of the head of the inverted rail at its side of the rail and to fit against the web of the inverted rail throughout the major height of the web.

18. In a temporary track extension unit the combination of inverted rails of usual cross section having heads, webs, and bases, with the latter facing upwardly, a tie construction releasably connecting said inverted rails thereon in inverted gauged relation, and a second tie construction having rail anchor clips in spaced relation thereon for releasably gripping the inverted rails in unobstructed relation with the normal bases thereof, at the outer sides of said inverted rails, said last mentioned tie construction being free of clamps thereon at the inner sides of said inverted rails.

19. In the railway art a tie construction for the purpose described, comprising a tie body of a length for receiving a pair of gauged rails thereon and having at one end thereof a rigidly affixed immovable rail anchor clip, and at the opposite end said tie having a movable rail anchor wedge clip, said tie between said clips being unobstructed with other rail anchor clips.

20. In the railway art a tie construction for the purpose described, comprised a tie body of a length for receiving a pair of gauged rails thereon and having at one end thereof a rigidly affixed immovable rail anchor clip, at the opposite end said tie having a movable rail anchor wedge clip, said tie between said clips being unobstructed with other rail anchor clips, said rigid and movable rail anchor clips being formed with upstanding rail anchor ends shaped to receive the head and web portions of inverted rails thereagainst.

21. In combination with a permanent trackway including ties having rails permanently affixed thereto, and a temporary extension trackway unit including inverted rails of substantially the same cross section as the permanently attached rails, ties detachably securing the inverted rails in properly gauged relation at a location beyond the permanent rails, and a tie detachably connecting the ends of the inverted temporary rails in overlapping engagement against the outer side of the permanent rails at a location between the rear ends of said inverted temporary rails and one of the ties to which the permanent rails are permanently affixed.

22. In combination with a permanent trackway comprising rails mounted on ties in usual relation, an extension unit for said trackway comprising a pair of inverted rails mounted on ties in proper spaced relation for slidably engagement with the permanent rails and a tie having a clamp at one end adapted to engage one of the inverted rails and a rotat-

able clamping clip at the other end adapted to engage the other inverted rail and clamp said extension rails against the permanent rails.

23. In combination with a permanent trackway, comprising rails mounted on ties in usual relation, an extension unit for said trackway comprising a pair of rails mounted on ties in proper spaced relation for slidable engagement with the permanent rails and a tie having means adjacent one end thereof adapted to engage the head and web of one of the inverted rails and a rotatable clip pivoted adjacent the other end of the tie adapted to engage the head and the web of the other inverted rail and clamp said extension rails against the permanent rails.

24. A railway track extension unit comprising a tie, an inverted rail having its head resting upon said tie and fastening clips mounted on said tie and engaging the web of said rail.

25. A railway track extension unit comprising a tie, an inverted rail having its head resting upon said tie and fastening means comprising a rotatable clamping clip mounted on said tie and adapted to be brought into engagement with the web of said rail.

26. A railway track extension unit comprising a tie, a rail having its head resting upon said tie and fastening means, including a rotatable clamping clip, mounted on said tie and adapted to engage the web of the rail on its opposite sides.
